UNITED STATES PATENT OFFICE

119,930

DESIGN FOR A TEXTILE FABRIC

Gladys B. Di Gangi, Elmhurst, N. Y., assignor to The Barbizon Corporation, New York, N. Y., a corporation of New York

Application February 3, 1940, Serial No. 89,974

Term of patent 3½ years

To all whom it may concern:

Be it known that I, Gladys B. Di Gangi, a citizen of the United States, residing at 82-01 Britton Avenue, Elmhurst, in the county of Queens, State of New York, have invented a new, original, and ornamental Design for a Textile Fabric, of which the following is a specification, reference being had to the accompanying drawing, forming part thereof.

The figure is a view of a textile fabric showing my new design.

I claim:

The ornamental design for a textile fabric, as shown.

GLADYS B. DI GANGI.
